UNITED STATES PATENT OFFICE

ADOLPH J. ROOS, OF CANTON, OHIO, ASSIGNEE TO THE DIEBOLD SAFE & LOCK COMPANY,
OF CANTON, OHIO, A CORPORATION OF OHIO

PROTECTIVE STRUCTURE

Application filed December 14, 1929. Serial No. 414,008.

My invention relates to protective structures for storing and protecting valuables, such as money, securities, documents, precious stones, precious metals, and the like, 5 against the hazards of explosion, fire, and predatory or riotous attacks by the use of impact tools, such as sledges or hammers, or by the use of the burning torch, or by the use of drills, explosives, saws and the 10 like.

Such protective structures are usually designated according to their size, as chests, safes, and vaults, and each includes, in general, walls which may comprise a portable 15 box, and which form a compartment within which the valuables are placed for storage and protection.

One wall of the protective structure is provided with an opening in which a door frame 20 is mounted, and a door is operatively hung for moving to and from closing position in the opening of the door frame, the door being equipped with a usual lock and bolt work for operation by persons authorized to have 25 access to the interior of the protective structure.

The present invention relates more particularly to portable protective structures, and such portable protective structures, as aforesaid, may be of varying sizes, and may include smaller structures usually classed as 30 chests, and having a capacity for a relatively small quantity of valuables, such as the daily receipts of stores, gasoline filling stations, and the like, and also may include the intermediate structures usually classed as 35 safes, the capacity of which is greater than that of chests, but which do not permit the entrance of individuals into their interior, and finally may include larger structures 40 ordinarily classed as vaults, whose size is sufficient to permit the entrance of one or more individuals into their interior.

From the standpoint of the economical 45 quantity production of such preferably portable protective structures, it is desirable that different materials be used for the construction of the door frame and door, and for the construction of the walls of the protective compartment.

That is to say, in addition to performing their structural and protective functions, the door frame and door must be operatively associated and accurately fitted with each other, and the door moreover carries or 55 includes the bolt-work which is operative for engagement and disengagement with bolt stops formed on the door frame.

In other words, the door frame and door and the parts operatively connecting them 60 and carried thereby, comprise mechanisms, all elements of which must be made accurately, and which are adapted for performing mechanical functions.

On the other hand, the remaining parts 65 of the protective structure, that is, the walls forming the storage and protective compartment, have only their protective and structural functions to perform, as distinguished from the mechanical functions of the parts 70 of mechanisms.

The objects of the present improvements include the provision of a protective structure in which the door frame and door may be made of materials, which may be very 75 expensive, but which may be best suited for performing the combined structural, protective, and mechanical functions thereof, and which door frame and door are adapted for convenient and cooperating connection 80 with walls forming a protective and storage compartment of any desired size, the compartment walls being formed of materials best suited for performing the structural and protective functions thereof, and 85 which may be less expensive than the materials of the door frame and door.

These objects are attained by the present invention, as is hereinafter claimed, and which may be stated in general terms as 90 comprising a protective structure including a door frame and door operatively mounted thereon, and the door frame and door being preferably made of an alloy metal, such as low carbon chrome alloy steel, which is 95 adapted for meeting the structural and protective requirements, as well as the mechanical requirements of the door frame and door, and the door frame and door being cooperatively connected in a novel manner with a 100

- door frame opening formed in one of a plurality of walls forming a storage and protective compartment of any desired size, the walls of the compartment preferably comprising a reinforced concrete monolithic shell interposed between a preferably cast inner lining shell of metal, and an outer metal case shell, and the reinforced concrete shell may be of any desired thickness and 5 mass for meeting the structural requirements of the compartment walls in combination with the inner and outer shells.

A preferred embodiment of the invention is illustrated in the accompanying drawings 10 forming part hereof, in which

Figure 1 is a vertical sectional view, as on line 1—1, Fig. 2 of a protective structure embodying the improvements hereof, and which is of the size generally classed as 15 chests;

Fig. 2, a vertical sectional view thereof, as on line 2—2, Fig. 1, with portions broken away to more clearly illustrate details of construction; and

Fig. 3, an enlarged horizontal sectional view thereof, as on lines 3—3, Figs. 1 and 2.

Similar numerals refer to similar parts throughout the several views.

The improved protective structure indicated generally at 10, as illustrated is of the size usually classed as a chest, and includes walls forming a storage and protective compartment 11. The walls are of novel composite construction, and include a bottom

30 wall indicated generally at 12, a top wall indicated generally at 13, a back wall indicated generally at 14, side walls indicated generally, respectively, at 15 and 16, and a front wall indicated generally at 17.

40 A door frame opening 18 is formed in the front wall 17, and a novel door frame indicated generally at 19 is positioned within the opening 18, and is connected, in a novel manner hereinafter set forth in detail, with 45 the front wall 17, the side walls 15 and 16 and the top wall 13.

The door frame 19 has a door opening 20 formed therein and a door 21 is hung upon the door frame as by a hinge 22 for swinging 50 to and from closing and fitting position in the door opening 20.

As illustrated the door 21 includes a flanged circular frusto-conical closure member 23 which is mounted upon a supporting ring 24 in a well known manner for rotation about a horizontal axis passing through the center of the preferably flanged frusto-conical opening 20, and the supporting ring 24 is carried by the hinge 22, and rotation of 60 the closure member 23 on the supporting ring is controlled by a dial lock indicated generally at 25.

The bolt work for the door, thus rotatably mounted on the ring 24, includes circumferentially spaced bolts 26 extending radially

70 from the rear of the closure member for engagement behind circumferentially spaced bolt stops 27 extending radially inwardly from the door opening and comprising portions of the rear flange thereof, there being notches in the door opening formed between the bolt stops 27, and permitting entrance of the bolts 26 therethrough when the door is being closed.

75 For further bolting the door, a bolt 28 is mounted for radial extension and withdrawal on the closure member 23, and is adapted for being extended and withdrawn into and from a suitable aperture 29 formed in the door frame, after the closure member 23 has been moved to closing position and rotated so that the bolts 26 engage the bolts stops 27.

80 The foregoing bolt work arrangement for the circular door is generally well known in the art, and other types of bolt work may be utilized, and also the door may be square or 85 rectangular as desired depending upon the size of the protective structure.

85 The door frame and door are preferably 90 made of a metal alloy such as low carbon chrome steel alloy, which after being hardened is very tough, hard, and resistant to heat, and is not affected by the usual hazards of 95 explosion, fire, or attacks by the use of impact tools such as sledges or hammers, or by the use of the burning torch, or by the use of 100 drills, explosives, saws, and the like.

105 It is of course necessary to provide relatively thick walls for the frame and door, and the usual method of making the frame and door from the aforesaid preferred alloys, is to cast the frame and the door, to perform the necessary machining operations thereon in the annealed state, and then to harden the 110 same.

110 The use of a single material for constructing the frame and the door avoids the relatively large manufacturing expense heretofore always associated with making explosion, fire, and burglar-proof doors and frames by the use of laminated plates or other 115 composite structures.

115 The cost of the aforesaid alloys is however too great to warrant their use for the compartment walls of the safe, which have as aforesaid only structural and protective functions to perform, as distinguished from the 120 mechanical functions as well as structural and protective functions which must be performed by the frame and door.

120 For attaining an economical construction for the compartment walls, the composite bottom wall 12 preferably includes an inner metal lining wall 12a, an outer metal case wall 12b, and an intermediate reinforced concrete structural and protective wall 12c.

125 The composite top wall 13 similarly includes an inner metal lining wall 13a, an outer metal case wall 13b, and an intermediate 130

reinforced concrete structural and protective wall 13c.

Likewise, the composite back wall 14 includes an inner metal lining wall 14a, an 5 outer metal case wall 14b and an intermediate reinforced concrete structural and protective wall 14c.

The side wall 15 similarly includes an inner metal lining wall 15a, an outer metal case 10 wall 15b and an intermediate reinforced concrete structural and protective wall 15c.

The side wall 16 likewise includes an inner metal lining wall 16a, an outer metal case wall 16b, and an intermediate reinforced concrete 15 structural and protective wall 16c.

Finally, the composite front wall 17 similarly includes an inner metal lining wall 17a, an outer metal case wall 17b, and an intermediate reinforced concrete structural and 20 protective wall 17c.

The inner metal lining walls 12a, 13a, 14a, 15a, 16a, and 17a, form an inner lining shell indicated generally at 30a which is preferably integrally formed by casting the walls of a 25 relatively inexpensive material, such as cast steel.

The outer case walls 12b, 13b, 14b, 15b, 16b, and 17b preferably form an outer case shell indicated generally at 30b which is preferably made of angle and plate, or angle and sheet construction.

The intermediate reinforced concrete structural and protective walls 12c, 13c, 14c, 15c, 16c, and 17c form an intermediate structural 35 and protective shell indicated generally at 30c which is preferably integrally poured between the inner lining shell and the outer case shell by properly positioning the inner shell 30a within the outer shell 30b and re- 40 moving one wall of the outer shell until the reinforced concrete shell 30c has been poured and is hardened, after which the removal wall of the outer case 30b may be reinserted in the case.

45 The inner preferably cast steel lining shell 30a is connected with the frame 19, and both the frame 19 and the inner lining shell 30a are connected with the reinforced concrete shell 30c by novel means which will now be 50 described.

A preferably cylindric tube 31 extends forwardly from the upper end 17a' of the front wall 17a, and telescopes preferably over a cylindric flange 32 extending rearwardly 55 from the frame 19.

As illustrated, the tube 31 is of substantial length, and forms a vestibule immediately at the rear of the door 20, and the upper end 17a' of the front wall 17a forms a partition 60 at the rear end of the vestibule tube 31. A door opening 33 is formed in the partition portion 17a' of the front wall 17a, and a door 34 is operatively hung thereon, whereby access may be had to the main compartment 65 11 from the interior of the vestibule 31.

A plurality of circumferentially spaced radially extending registering apertures are formed in the telescoping tube 31 and flange 32.

70 A connecting and anchor spider bar 35 extends, preferably with a drive fit, through each set of registering apertures and beyond the outer surface of the tube 31 a substantial distance into the adjacent reinforced concrete shell 30c, and the reinforcing 36 of the reinforced concrete is preferably secured as by welding to the outer ends of the bars 35.

75 The spider bars 35 in addition to their force fit in the registering apertures of the tube 31 and the flange 32, are preferably welded from the outside to the outside of the tube 31.

80 The spider bars 35 thus comprise novel means for connecting the door frame with the inner lining shell and anchoring both the frame and the inner lining shell in the reinforced concrete structural and protective shell.

85 When desired, the outer surface of some of the walls of the inner lining shell 30a may be spaced from the inner surface of some of the walls of the reinforced concrete shell 30c, thereby forming a gas chamber 37 in which material may be placed which will release 90 obnoxious or poisonous gas through any opening forced through the outer case shell and the reinforced concrete shell into the gas chamber.

95 The reinforced concrete shell 30c in itself, when made of the proper thickness and with the proper amount of reinforcing, as is known in the art, performs all the desired structural and protective functions for the compartment walls.

100 Its use in the present instance for the preferably portable protective structures, provides a sufficient mass of material economically to prevent the carrying away of the protective structure by thieves.

105 By the present invention, the door and door frame of the novel protective structure may be made as aforesaid of the best material for meeting the particular structural, protective and mechanical requirements thereof, and the door and door frame are connected and anchored in a novel manner with the novel composite shell of economical construction, and within which is formed the storage and protective compartment.

110 Accordingly a door frame and door of one size may be used with a composite shell of any desired size, thereby affording further economies in manufacture.

115 The structural and protective shell 30c is preferably made as aforesaid of reinforced concrete, which is one species of material of a general class which may be termed reinforced monolithic material, and which may include reinforcing bars embedded in a monolithic shell, which as illustrated is preferably 120 130

concrete but which may include any other of the known varieties of plastics which harden into a stone-like structure.

I claim :

- 5 1. A protective structure including monolithic walls embodying a shell having a storage and protective compartment formed therein, one of the walls having an opening formed therein, a vestibule member extending 70 through the opening, a door frame adapted for operatively mounting a door thereon, a member extending from the door frame and overlapping the vestibule member, means connecting the overlapping members to each 75 other and anchoring in the monolithic shell, reinforcing means embedded in the monolithic shell, and the anchoring and connecting means being secured to the reinforcing means.
- 10 2. A protective structure including monolithic walls embodying a shell having a storage and protective compartment formed therein, one of the walls having an opening formed therein, a vestibule member extending through the opening, a door frame adapted for operatively mounting a door thereon, a member extending from the door frame and overlapping the vestibule member, there being a set of registering 80 apertures in the overlapping members, and a connecting and anchoring spider bar extending through the apertures and radially outwardly from the members into the monolithic shell.
- 15 3. A protective structure including monolithic walls embodying a shell having a storage and protective compartment formed therein, one of the walls having an opening formed therein, a vestibule member extending 85 through the opening, a door frame adapted for operatively mounting a door thereon, a member extending from the door frame and overlapping the vestibule member, there being sets of registering apertures in the overlapping members, and a connecting and anchoring spider bar extending through the apertures and radially outwardly from the members into the monolithic shell, reinforcing means embedded in the monolithic shell, and the anchoring and connecting bar 90 being secured to the reinforcing means.
- 20 4. A protective structure having monolithic walls which form a shell having a storage and protective compartment, one of the walls having an opening formed therein, a tubular metallic member extending through the opening, a door frame adapted for operatively connecting a door thereon, said door frame having a part telescoped into said 95 tubular member, reinforcing means embedded in the monolithic shell, and metallic members secured to said reinforcing means and securing said frame and said tubular member to each other.
- 25 5. A protective structure having mono-

lithic walls forming a shell having a storage and protective compartment therein, one of said walls having an opening formed therein, a metallic receptacle embedded in said monolithic shell and formed with an integral tubular member projecting into said opening, a door frame mounted in said opening, a door in said door frame and metallic bars projecting through said door frame and said tubular member and projecting into said monolithic shell, said metallic bars securing said door frame to said tubular member and anchoring said metallic shell in said monolithic shell, and reinforcing means embedded in said monolithic shell and secured to said metallic bars.

6. A protective structure having monolithic walls which form a shell having a storage and protective compartment therein, a one-piece metallic shell disposed within said compartment and provided with an integral tubular extension projecting into said opening, a door frame fixed to said tubular extension, reinforcing means embedded in said monolithic shell, and a plurality of rods extending from said tubular extension into said monolithic shell to anchor said metallic shell therein, said reinforcing means being secured to said metallic rods.

In testimony that I claim the above, I have 95 hereunto subscribed my name.

ADOLPH J. ROOS.
